UNITED STATES PATENT OFFICE.

ERASTUS E. WINKLEY, OF LYNN, MASSACHUSETTS.

WELT-BUTTING MACHINE.

1,018,858.

Specification of Letters Patent. Patented Feb. 27, 1912.

Application filed June 8, 1908. Serial No. 437,281.

To all whom it may concern:

Be it known that I, ERASTUS E. WINKLEY, a citizen of the United States, residing at Lynn, in the county of Essex and State of Massachusetts, have invented certain new and useful Improvements in Welt-Butting Machines; and I do hereby declare the following to be a full, clear, and exact description of the invention, such as will enable others skilled in the art to which it appertains to make and use the same.

This invention relates to machines for operating on welted boots and shoes, after the welt has been stitched on, to prepare the shoe for the reception of the outsole. The operations at this time include the trimming to proper length and form of the butt ends of the welt, and for this reason this type of machine is known in the art as a "welt butting machine."

In butting welts it is desirable to provide the severed ends with a bevel so that the outsole may be smoothly laid. In the machines heretofore constructed, in order to obtain a bevel, the welt ends have been supported on a plane surfaced cutting plate thrust beneath the welt which sustain said ends at an angle to the plane of the stroke of the welt butting cutter. The cutter is then moved across the cutting plate in a direction to pass through the thickness of the welt thus forming the desired bevel. If the welt is at all wet so that it may stretch, as frequently happens owing to its recent handling at the inseam sewing machine, a ragged edge is apt to be left at the end of the welt by the cutter. It may also happen under these conditions that the welt will not be completely severed owing to the smooth, unbroken surface in opposition to the stroke of the cutter which permits the undesired stretching of the welt, ahead of the cutting stroke, to occur. Owing to the fact that there is a portion of the margin of the upper remaining unsecured between the ends of the inseam and the foremost heel seat lasting tacks at each end of the breast line, the upper at these points is loose and tends to draw the ends of the welt outwardly and away from proper cutting position. The welt ends also generally curve outwardly from the

edge of the insole and at varying angles. It is difficult to butt the welt ends uniformly while they remain in this position.

The general object of the invention is to provide a machine which will unfailingly completely sever the welt ends uniformly relatively to each side of the shoe and uniformly on each shoe and with an even and sharply defined cut no matter what condition the welt may be in.

In varying styles of shoes it is desirable that the welt ends be beveled at greater or less angles to obtain the desired close contact between the outsole and insole when laying the outsole according to the varying conditions of the work. In accordance with a further object of the invention, means is provided to permit a variation in the angle between the plane of the cutting stroke of the welt butting cutter and the surface of the welt so that varying angles, and thus also varying lengths, of bevel may be obtained.

Another feature of the invention consists in the provision of means for removing from interference with the cutters the ends of the welt or other portions of the shoe severed by the action of the cutting instrumentalities so that the working parts will not become clogged up.

To the attainment of the ends above described, in the most desirable form of the invention now known to the inventor, the clean severance of the welt ends is obtained by providing the cutting plate with an abutment or shoulder, on which the welt end rests, located at the end of the stroke of the welt butting knife and which rigidly supports the welt end against the thrust of the knife as the cut is being completed. Preferably the abutment is provided with a knife edge and is undercut so that while the welt butting knife may pass sufficiently far beneath it to cause the two parts to act as shear blades and insure a severance of the welt, nevertheless the cutter is prevented from being dulled by a contact with the abutment. In order to place the welt in proper relation to the cutters so that a uniform severance will occur devices are provided on each side of the shoe comprising

blades arranged to engage in the crease between the welt and upper adjacent to the end of the welt, and press the welt inward into proper position for cutting. The action of these blades also tightens the upper at the unsecured portion between the ends of the inseam and the heel seat tacks. In order to vary the relation between the surface of the welt and the plane of the stroke of the welt butting knife, the cutter plate or welt support is made angularly adjustable about an axis transverse to the direction of said cutting stroke, thus permitting the surface of the welt to be brought more or less toward a position of co-incidence with said cutting plane. If the severed portion of the welt is not removed from the cutter plate, it is liable to clog up the working parts and prevent a proper butting of the welt on the next shoe presented to the machine. A welt butt ejector is therefore provided which engages the butt after it has been severed and sweeps it toward the center of the heel so that when the shoe is removed from the machine the severed butt is carried away with it.

To the accomplishment of these objects and such others as may hereinafter appear, as will be readily understood by those skilled in the art, the invention comprises the features and combinations of parts hereinafter described and particularly pointed out in the appended claims.

The various features of the invention will be best understood from a description of one embodiment thereof, such, for instance, as illustrated in the accompanying drawings, in which:

Figure 1 is a side elevation of the entire machine. Fig. 2 is a plan of the head of the machine. Fig. 3 is a side elevation of Fig. 2. Fig. 4 is a section in elevation on the line 4—4 of Fig. 2, showing the relation of the moving parts before the welt is butted. Fig. 5 is a section in plan on the line 5—5 of Fig. 3, showing the adjusting mechanism for the back gage. Fig. 6 is a detail of one of the cutter carrying heads, with its cover plate removed, and showing the relation of the moving parts at the completion of the stroke of the welt butting cutter. Fig. 7 is a front elevation of the parts shown in Fig. 6. Fig. 8 is a plan of the heel portion of a shoe, showing the operation of the heel seat leveling and stitch cutting knives. Fig. 9 is a transverse section on the line 9—9 of Fig. 8. Figs. 10 and 11 are diagrammatic views showing the action of the welt butting cutter in butting a welt, and Fig. 12 is a plan of the welt butt ejecting device and the adjacent parts.

In the embodiment of the invention selected for illustrative purposes, a frame 2, which carries the working parts, is mounted upon a base or stand 4, arranged to sup-

port the working parts at a suitable height convenient to the operator. In the preferred arrangement of the machine, means is provided for butting both the free ends of the welt simultaneously, and to this end, 70 the frame 2 is provided with a pair of vertically arranged pivots 6 (Fig. 2), and on each of these pivots there is mounted a cutter carrying head 8. Each of these heads supports a welt butting cutter, to be described hereinafter. The arrangement is such that the shoe is positioned, sole up, between the heads 8 and they are arranged to engage the upper at the counter, and are also adapted to engage varying sizes of 80 shoes. To this latter end, each of the heads 8 is provided at its rear end with a segment 10, which segments intermesh, as shown most plainly in Fig. 2. The heads 8 are pinned to the pivots 6, which pivots act as 85 rock-shafts to turn the heads about the pivots and place them at a proper distance apart to receive the particular shoe to be operated upon. The intermeshing segments 10 permit the heads to be moved apart 90 simultaneously and evenly. One of the pivots 6 has pinned to it a crank 12 (Fig. 2), to which is connected one end of a link 14, the other end of which is in turn connected to one arm of a bell crank lever, fulerumed at 18 on the frame 2. To the other arm of the bell crank lever 16 is pivoted a connecting rod 20, extending downwardly and pivotally connected at its lower end to a treadle lever 22 in a stand 24 at the base of the machine. The rod 20 passes through a lug 26 on the base 4, and is provided above the lug with a coiled spring 28, which bears at its lower end on the said lug and at its upper end against an adjustable collar on the rod 105 20. The rod 20 is also provided with a second adjustable collar below the lug 26.

The construction of the parts just described is such that the spring 28 normally maintains the treadle lever 22 in its upper position, this position being determined by contact of the lower collar of the rod 20 with the lug 26. With the treadle lever 22 in its upper position, the bell crank lever 16 is operated to move the rock-shaft formed by the pivot 6 to which the crank 12 is attached, in a direction to close the heads 8. The action of the spring 28 on the heads 8 is further aided by a strong coiled spring 30 (Fig. 2) connected at its ends to a pin 110 120 on each of the heads 8, and tending always to draw the said heads together.

Mounted in the frame 2 and between the heads 8 is a back gage 32 (Fig. 4), carried on the end of a slide 34 guided in lugs on the frame. This back gage may be adjusted in and out by the following mechanism: The slide 34 toward its rear end is provided with a depending arm 36, to the lower end of which is pivoted the rear end of a link 125 130

38. The forward end of this link is in turn pivoted to the central portion of a lever 40, fulcrumed on one of the rock shafts 6. The lever 40 extends transversely across the machine, and is provided at its free end with a handle 44, provided with the usual spring-pressed detent. This detent is adapted to engage with the teeth of a rack 46 mounted on the frame 2. By releasing the detent 45 from its rack, the lever 40 may be moved about its fulcrum, thereby in turn moving the back gage in and out relatively to the machine frame. The purpose of this adjustment is to enable the operator to place 50 the heel end of the shoe relatively to the welt butting cutters, so that the cutters will operate to butt the welt at the desired distance from the back of the heel. In practice it is preferred to butt the welt at a point 55 about opposite the breast line of the heel. The distance of this point from the back of the heel varies in different sizes or styles of shoes, and as the cutting points of the welt butting cutters in the heads 8 is fixed, it is obvious that some relative adjustment 60 between the back gage and the cutter must be provided, in order to obtain a severance of the welt at the point desired with relation to the particular shoe being operated 65 upon.

In order to position the shoe for a proper butting of the welt, the back gage 32 is first adjusted to suit the particular size or style of shoe being operated on, and the treadle lever 22 is then depressed to open the cutter carrying heads 8 sufficiently to permit the operator to place the shoe, sole up, between them, with its heel against the back gage. Suitable welt supports, to be 70 hereinafter described, are placed beneath the free ends of the welts to sustain them in a proper position to receive a beveled cut from the action of the welt butting cutters.

The welt butting cutters are mounted in 75 the heads 8 for a movement longitudinally of the shoe and the welt, and are actuated by the following mechanism: The frame 2 is provided with a longitudinal guideway 48, in which is mounted a slide 50 (Fig. 4). The slide 50 is provided at its upper side 80 with a cross bar 52 (Fig. 2), to each end of which there are pivotally connected the rear ends of links 54, the forward ends of which links are in turn pivotally connected to actuators, hereinafter described, mounted in the heads 8 for the welt butting cutters. To the forward end of the slide 50 is pivoted one end of a link 56, having pivoted to its other end one arm of a bell crank lever 58, 85 fulcrumed on a horizontal pivot pin 60 in the frame 2. To the other arm of the bell crank lever 58 there is pivoted a depending rod 64 pivoted at its lower end to a treadle lever 66, fulcrumed in a stand 68 at the base of the machine. The rod 64 is pro-

vided with a loose collar 68, held from downward movement by an engagement with lugs 70 of the machine base 4. The treadle lever 66 is normally held upwardly by means of a coil spring 72, bearing at its lower end upon the collar 68 and at its upper end against an adjustable collar on the rod 64. This spring normally maintains the slide 50 at the forward end of its guide 75 48, and, in turn, the welt butting cutter actuators in their forward, or inactive, position in the heads 8. A stop is provided in a convenient position to limit the outward movement of the slide 50. After the shoe has been properly positioned between the cutter carrying heads, the treadle lever 66 is depressed and its movement oscillates the bell crank lever 58 in a direction to move the slide 50 backwardly and thus carry the welt butting cutters toward the heel of the 80 shoe to perform their cutting office.

The construction and operation of the welt butting cutters and cooperating parts will now be described, but as these parts are the same for both of the heads 8, it will suffice to describe the parts in one of these heads only.

Referring now to Figs. 4, 6 and 7, it will be seen that each of the heads 8 comprises a box-like structure open at its inner side 95 and provided on this side with a cover plate 74 (Fig. 4) having, however, a suitable opening through which the operative parts project inwardly. At the lower portion of the head 8, and projecting inwardly, is the 100 welt support or cutter plate 76, adapted to be thrust beneath the free end of the welt at the time the shoe is placed in position. This welt support is provided with a blunt edge 78 (Fig. 7), which enters the crease between the welt and the upper (Fig. 9), and bears against the inseam stitches. By an inspection of Fig. 8 it will be seen that there is a space between the ends of the inseam and the beginning of the line of lasting 110 tacks at the heel where the margin of the upper is unsecured to the insole. The upper at this point is therefore quite loose, and the highly tensioned portions of the upper at each side of it tend to 115 draw outwardly the margin of the upper at this point, and, with it, the end of the welt. Under these conditions, if the welt were butted by a knife moving longitudinally of the shoe, the cut would not be 120 made square across the welt. The engagement of the blunt edges 78 of the welt supporting plates 76 with the inseam on each side of the shoe, acts through the force of the strong springs 28 and 30, to tighten the 125 upper materials at the end of the welt, where they are unsecured, and to force the welt ends inward into a position for proper butting. The cutter plate 76 is provided toward its rear side, as is most clearly shown 130

in Fig. 12, with a plate 80, which extends under the extremity of the welt and supports it (Fig. 10). This plate is raised at its forward end somewhat above the level of the surface of the cutter plate, thus forming a shoulder or abutment on said plate, the upper surface of which projects above the plane in which the welt butting knife travels. This shoulder is preferably undercut somewhat and is formed with a knife edge for a purpose hereinafter described.

The welt butting cutter 82 projects transversely from the head 8 and is provided with a knife edge directed toward the rear of the machine and the heel end of the shoe. This cutter is suitably mounted in the forward end of a cutter carrier, which is shown as a slide 84 (Fig. 6) provided with a slot 86 at its rear end, through which is passed a screw 88, acting as a fulcrum for said slide. The cutter carrier may therefore oscillate in the head about the screw 88 as a center, or it may reciprocate in the head past said screw. The slide 84 is provided with a depending lug 90 at its rear end, which is engaged by a spring-pressed plunger 92 mounted in a socket 94 on the frame 2. The action of this spring-pressed plunger keeps the rear end of the slot 86 normally against the screw 88 and also maintains the cutter 82 raised away from the shoe, so that it will not interfere with a proper positioning of the shoe between the cutter carrying heads. Owing to the high instep and consequent pronounced angle at the shank between the forepart and heel seat of many shoes, great difficulty would be experienced in positioning the shoe were the cutter maintained normally in its cutting position. The actuator for the welt butting cutter, which has been described as connected to the forward end of the link 54, is shown, (see Fig. 6), as a slide 96 provided at its forward end with a wedge surface 98 adapted to engage a co-operating wedge surface 100 on the forward end of the cutter carrier 84. When the treadle lever 66 is in its raised position, the actuator slide 96 is in its forward position, as shown in Fig. 4, and the spring-pressed plunger 92 is permitted to operate to maintain the cutter 82 elevated, as shown in said figure. On depression of the treadle 66, however, the actuator slide 96 is moved backwardly horizontally, which carries the wedge surface 98 past the wedge surface 100 and operates to move the cutter carrier 84 downwardly about its pivot 88, the action of the spring-pressed plunger 92 at this time preventing any movement of the cutter carrier past said pivot. This downward movement of the cutter continues until a lug 102 on the cutter carrier comes in contact with a shelf 104 at the inner side of the recess in the cutter carrying head, in which the cutter car-

rier operates. At this time the actuator slide 96 has been moved a sufficient distance to bring a lug 106 on its lower side in contact with a similar lug 108 projecting from the upper surface of the cutter carrier. The welt butting cutter has now been moved to the position shown in Fig. 10, just prior to the commencement of its cutting stroke. Any further backward movement of the actuator slide 96 now serves merely to tightly clamp the cutter carrier 84 between the three bearing points mentioned, namely, the two wedge surfaces 98 and 100, the lug and the shelf 102 and 104, and the two lugs 106 and 108, so that no further oscillation about the pivot 88 is permitted. The cutter carrier 84 is free, however, to be moved in a horizontal plane longitudinally of the shoe, and the further backward movement of the actuator slide 96 operates to so move said cutter 82 against the force of the spring-pressed plunger 92 and past the pivot 88, which movement is permitted by the slot 86. The treadle 66 is depressed to the limit of its movement, which operates to draw the cutter 82 to a position beneath the undercut abutment or shoulder 80, as shown in Figs. 6 and 11. As the end of the welt is held rigidly by this shoulder against the thrust of the knife, and as the welt butting cutter moves in a plane beneath the knife edge formed on said abutment, the two parts act as shearing blades, to cleanly and sharply sever the welt, no matter what its condition of temper may be. It will be noted that the link 54 connected to the actuator slide 96 is adjustable, so that the stroke of the cutter may be varied. By this means the stroke can be controlled so as to stop as the cutter reaches a position beneath the undercut shoulder 80 after shearing off the welt end but before the edge of the cutter has come into contact with the base of the shoulder. The advantage of a support for the welt end against the thrust of the cutter without a dulling of the cutter is thus secured.

The cutter carrier 84 is provided with a pin 110 projecting horizontally therefrom, on which is loosely mounted a lever 112, the forward end of which projects to a position 115 in front of the welt butting cutter 82. This lever is formed at its forward end to act as a presser-foot, which owing to its location smooths out the welt and lays it evenly upon the welt support 78 prior to the action of the cutter. The presser-foot is spring-pressed against the welt by means of a suitably mounted spring 114. The downward movement of the presser-foot is limited by the rear end of the lever 112 contacting with a lug 116 on the cutter carrier 84.

It will be noted that in the present instance a beveled cut on the end of the welt is obtained by moving the welt butting cutter in a plane substantially parallel to the 130

face of the welt and supporting the welt at an angle to the plane of the cutting stroke. Different kinds or styles of shoes require that the bevel on the welt end be more or less oblique, and therefore means is provided for varying the angle at which the welt may be supported relative to the plane of the cutting stroke of the welt butting cutter. To this end the welt support 76 is provided with a cylindrical shank 118, mounted in a horizontal journal in the head 8, and held in any position of angular adjustment by means of a clamp screw 120 passing through the ends of a split ring at the outer end of the journal. It is obvious that if the shank of the welt support 118 be angularly adjusted to a position such that the surface of the support is in the same plane as the stroke of the cutter, no bevel whatever will be obtained. On the other hand, an angular relation obtaining between the surface of the welt support and the plane of the stroke of the cutter will produce a bevel cut, and the obliquity of the bevel will be increased according to the increase in the angle named.

Referring now to Fig. 8, it will be seen that a short portion of the upturned lips to which the welt is secured by the inseam, projects beyond the end of the stroke of the welt butting cutter. As the stroke of the cutter stops at about the breast line, these protruding materials are within the area of the sole termed "the heel seat". It is desirable that the heel seat be, as far as possible, a plane surface so that the outsole may be laid smoothly thereover and thus provide an even seat for the heel. As the stroke of the welt butting cutter is not long enough to sever from the heel seat the protruding materials just described, other means are provided for severing these materials and thus accomplish the desired leveling off of the heel seat. To perform this function, it is convenient to make the plates 80 project beyond the welt supports and form their inner edges as knife edges 122, which, as the heads 8 are drawn together when the shoe is positioned, are forced through the materials protruding from the heel seat, as shown in Fig. 9, thus leveling off the heel seat even with the surface of the upper.

When the welt is being stitched on, the operator at the inseaming machine does not usually exercise any great care in either starting or stopping the inseam at a particular point, and therefore it frequently extends back of the breast line of the heel and therefore beyond the point where the welt is to be butted. This is undesirable, as if these extra inseam stitches are not severed, the butted welt and will remain secured to the shoe. The knife edges 122, therefore, very conveniently perform the function of severing any inseam stitches which extend beyond the end of the stroke of the welt butting

cutters so that said cutters can not only remove the butted end of the welt, but can also remove from attachment to the welt any of the protruding materials which have been severed from the heel seat by the action of the knife edges 122. It will be noted that owing to the provision of separate treadles, the heel seat is leveled and the inseam stitches are severed at the time the shoe is placed in position and before the welt butting cutters are operated.

It is, of course, desired to operate these machines at as high a rate of speed as it is possible to introduce shoes thereto, and therefore means should be provided to prevent the severed portions of the welt from getting between the moving parts and thus clogging the operation of the machine. To this end an ejecting device has been provided which preferably is operated by the return stroke of the welt butting cutters after the treadle 66 has been released. This ejecting device is shown most clearly in Figs. 4 and 12. It is the same for both heads, and a description of the device on one of the heads will be sufficient. The head 8 is provided with a vertically arranged pin 124, in which is journaled an arm 126 projecting forwardly and extending to a point just above the plate 80. The vertical journal for this arm is provided with a lug 128 near the top of the head 8, and this lug and the head are connected by a spring 130 which maintains the ejector arm 126 normally in a position against the inner face 100 of the head 8. The lug 128 is provided with any convenient form of latch 132 which is mounted to yield backwardly relatively to its support, but which on being engaged in a direction to move it forwardly, will also move the ejector arm 126 with it. The actuator slide 96 for the welt butting cutter is provided with a trip arm 134 having a projection adapted to engage the latch 132 on the cutting stroke of the welt butting cutter, at which time the latch yields and permits the trip arm to move past it without any movement of the ejector. As the actuator slide 96 moves in the opposite direction, however, the lug on the trip arm reengages the latch 132 on its other side, and acts to move it around the pivot 124 and against the force of the spring 130, at the same time moving the ejector arm 126 quickly inward toward the center of the shoe. After the passage of the trip arm the spring 130 returns the ejector arm to its normal position. As the welt at this time has been butted, the ejector arm acts to dislodge the severed portion of the welt and parts attached thereto, and throw them inwardly on to the heel seat of the shoe and out of the path of the cutter. Thus when the shoe is removed the severed portions of the welt are removed with it, thereby preventing any

danger of such portions clogging up the machine and preventing its rapid operation.

Although the machine has been described as being adapted to operate on both of the free ends of the welt simultaneously, it will be readily apparent to those skilled in the art that many of its features may be used in a machine which operates on only one welt end at a time, and therefore it should be distinctly understood that, where the context permits, the terms of the appended claims should be interpreted as being directed to a machine of either character named. Furthermore, where in the claims the term "cutter plate" is used, it will be understood that the claims are not intended to be limited to the use of the particular device used for purposes of illustration and explanation, but that the term is intended to cover a member of any form which is introduced between the welt and the upper, and participates in the operations upon the welt.

Nothing herein contained is to be construed as limiting this invention in the scope of its application to use in connection with the particular machine or the particular mode of operation, or both, selected for purposes of illustration and explanation.

While the particulars of construction herein set forth are well suited to one form of the invention, it is not to be understood that these particulars are essential, since they may be variously modified within the skill of the artisan without departing from the true scope of the actual invention as defined in the following claims.

What is claimed as new is:

1. A machine for butting welts having in combination, a welt butting cutter above the welt, a cutter plate beneath the welt to support it in position to be beveled by the stroke of the cutter, and an abutment or shoulder constructed and arranged to rigidly support the welt end against the thrust of the cutter as the cut is being completed.

2. A machine for butting welts comprising a cutter plate adapted to be thrust beneath the welt and support it in a position to facilitate the production of a beveled butting cut, said plate having an abutment or shoulder to rigidly support the welt end against the thrust of the cutting stroke when said end is severed.

3. A machine for butting welts having in combination, a welt butting cutter above the welt, a shear blade beneath the welt upon which its extremity is supported, and means for guiding the cutter in a direction to pass beneath the shear blade when butting the welt.

4. A machine for butting welts having in combination, a welt butting cutter, a welt support adapted to be thrust beneath the welt end and sustain it at an angle to the

plane of the stroke of the cutter and means to cause said cutter to travel in a plane below the upper surface of said support.

5. A machine for butting welts having in combination, a welt butting cutter, a welt support forming an undercut abutment or shoulder to rigidly support the extremity of the welt at the end of the stroke of the cutter, and means for adjusting the length of stroke of the cutter to prevent dulling the cutter by contact of its edge with the abutment.

6. A machine for butting welts having in combination, a welt butting cutter movable longitudinally above the welt, a welt support beneath the welt to sustain the welt end in position to be beveled off by said cutter, and provision for varying the angle between the planes of the surface of the support and the stroke of the cutter, to vary the angle at which the bevel is made.

7. A machine for butting welts having in combination, a welt butting cutter movable in a plane substantially parallel to the insole, and a cutter plate beneath the welt to sustain the welt end at an angle to the insole to provide a beveled cut, said plate being adjustable to vary the angle at which the welt end is sustained whereby the angle of the beveled cut is varied.

8. A machine for butting welts having in combination, a welt cutter movable in a plane substantially parallel to the insole to butt the welt and normally somewhat above the welt to facilitate positioning of the shoe, and means for moving said cutter vertically toward the welt into a position in advance of the cut before the commencement of its welt butting movement.

9. A machine for butting welts comprising a welt cutter movable in a direction to butt the welt, a pivotally mounted carrier therefor above the welt and movable toward and from the shoe, and cutter actuating means constructed and arranged to first oscillate said cutter carrier about its pivot to position the cutter and then to lock said carrier against further oscillation during the cutting movement.

10. A machine of the class described having in combination, cutting means for butting both free ends of the welt, and means cooperating therewith and acting from each side of the shoe for severing the surplus material from the heel seat portion of the shoe.

11. A machine of the class described having in combination, a pair of cutters acting from opposite sides of the shoe and substantially in the plane of the insole for leveling off the materials protruding from the heel seat portion of the shoe, and a pair of welt butting cutters for removing the welt ends from the shoe and also the materials severed from the heel seat by the leveling cutters.

12. A machine for butting welts having

- in combination, a reciprocating welt butting cutter, and an ejector controlled by the return movement of the cutter to engage and dislodge the severed welt butt. 12. A machine of the class described having in combination, means acting in substantially the plane of the insole for tightening the upper of a welted shoe adjacent to the ends of the heel stiffener at the opposite sides of the shoe simultaneously to place the welt in normal position, and means for butting the welt while so held in its normal position. 13. A machine of the class described having in combination, a welt butting cutter, means to support the welt end in a position to be beveled off by a stroke of said cutter, and means for varying the angular relation of said cutter and its support to vary the angle at which the welt end is beveled. 14. A machine of the class described having in combination, a welt butting cutter, and welt supporting and positioning means arranged to engage the stock in the welt crease adjacent the end of the inseam from opposite sides of the shoe and move the welt inward into its normal position preparatory to the butting operation. 15. A machine of the class described comprising a cutter on each side of the shoe with their cutting faces substantially parallel to the bottom of the shoe, said cutters being arranged for movement transversely of the shoe under the welt for planing the stock of the inseam adjacent to the heel seat substantially level with the upper on the shoe bottom. 16. A machine of the class described having in combination, a welt butting cutter, a stitch cutter, and actuating mechanism for said cutters arranged to permit the stitch cutter to be operated in advance of the welt butting cutter. 17. A machine of the class described comprising a welt supporting device adapted to be thrust beneath the welt having a part formed to apply pressure transversely through the inseam and a part sharpened and formed to cut the stitches of the inseam back of where the pressure is applied. 18. A machine of the class described having in combination, stitch cutters at opposite sides of the shoe, means for actuating said cutters to sever the inseam stitches, and a back gage to control the distance from the heel end of the shoe at which the stitches are severed on each side. 19. A machine of the class described having in combination, a welt butting cutter, actuating means therefor, and a cutter plate co-operating therewith movable transversely of the shoe toward and from a position in the crease between the welt and the upper. 20. A machine of the class described having in combination, a pair of welt butting cutters, cutter plates adapted to enter the crease between the welt and the upper at opposite sides of the shoe, means for moving the cutter plates transversely of the shoe toward and from operative position, and means for actuating the welt butting cutters. 21. A machine of the class described having in combination, a pair of welt butting cutter carrying heads, means to move said heads apart to permit positioning of the heel end of a shoe therebetween and to return said heads to a position where said cutters are in operative position, and actuating means for said cutters. 22. A machine for butting welts having in combination, a welt butting cutter, means to support the welt end in a position to be beveled off by a stroke of said cutter, and means for varying the angular relation of said cutter and its support to vary the angle at which the welt end is beveled. 23. A machine of the class described comprising, welt butting means arranged to permit the shoe to be moved endwise for positioning it relatively thereto, a back rest for the shoe, independent devices for supporting the butt end of the welt in proper relation to the welt butting means, and provision for holding said devices out of welt engaging position as the shoe is being positioned. 24. A machine of the class described comprising, means for butting a welt, and means adapted to engage the welt and movable transversely of the shoe into and out of engagement with the welt for moving it across the shoe into position for the butting operation. 25. A machine of the class described having in combination, means for removing surplus stock from above the heel seat comprising two cutters, and means to actuate one of the cutters to sever a portion of said stock from the heel seat and support it in position for removal from the heel seat by the other cutter. 26. A machine of the class described, having, in combination, a pair of heads one at each side of the machine, means to move said heads apart to permit positioning of the heel end of a welted shoe therebetween, a welt butting cutter carried by each of said heads, and means to move said heads inward after a shoe has been positioned, to bring said cutters concurrently into cutting relation with the welt ends. 27. A machine of the class described, having, in combination, means at opposite sides of the shoe engaging in the welt crease to tighten the upper about the last and position the butt ends of the welt on the insole, welt butting cutters movable over said means in a plane to bevel the welt ends, and yielding welt pressers mounted in advance of said cutters to engage the upper surface of the welt. 28. A machine of the class described, having, in combination, cutters for butting the two ends of a welt concurrently, and cutter plates co-operating therewith, extending in the welt crease at each side of the shoe at and adjacent the end of the inseam and also

inward over the insole and beneath the unsecured ends of the welt.

29. A machine for butting welts, having, in combination, a welt butting cutter, and a welt butt ejector, operating to dislodge the severed welt butt by a movement across the path of movement of the cutter.

30. A machine of the class described, having in combination a welt butting knife, means for actuating the knife, and a guard plate movable transversely of the shoe toward and from an operative position in the welt crease.

31. A machine of the class described, having in combination welt butting knives, guard plates adapted to enter the welt crease at opposite sides of the shoe, means for moving the guard plates transversely of the shoe toward and from operative position, and means for actuating the knives over the guard plates.

32. A machine of the class described, having in combination welt butting knives, guard plates adapted to enter the welt crease at opposite sides of the shoe, and means for actuating the guard plates and the knives having provision for moving the plates into operative position before the knives are advanced.

33. A machine of the class described, having in combination a device arranged to engage the shoe in the inseam adjacent to the end of the welt, means for actuating said device to position the end portion of the welt transversely of the shoe and hold it pressed in, and a welt butting knife for beveling the welt.

34. A machine of the class described having a welt butting cutter and means arranged for movement transversely of a shoe to engage the shoe stock in the welt crease on the two sides and position the welt.

35. A machine of the class described having means for butting a welt, supports for the two welt butts, and connected mechanism for actuating said two supports together transversely of the shoe bottom toward operative position.

36. A machine of the class described having welt butting means, means for supporting the welt while it is being acted upon, and manually controlled means for moving the support toward and from welt supporting position.

37. A machine of the class described having means for butting a welt and means movable transversely of the shoe toward and from engagement therewith to position the welt for the butting operation.

38. A machine of the class described having means for butting a welt, welt positioning means, means for moving said positioning means away from the shoe and means under control of the operator to move the positioning means toward the shoe.

39. A machine of the class described having means for butting a welt, and means movable laterally from and toward position to engage the shoe in the welt crease in front of the welt butting point.

40. A machine of the class described having means for butting a welt, positioning devices and mechanism for actuating said devices transversely of the shoe to engage the shoe in the welt crease.

41. A machine of the class described having means for removing surplus stock at the rear end of the inseam and means to position the surplus stock transversely of the shoe preparatory to the operation of said first mentioned means.

42. In a machine of the class described, cutters arranged for movement transversely of a shoe from opposite directions and means for actuating said cutters to cut the stitches of the inseam.

43. In a machine of the class described, means for removing surplus stock at the ends of the inseam, said means being arranged for movement transversely of the shoe from an inoperative relation to the shoe into an operative relation thereto and mechanism for actuating said means to do its work.

44. A machine of the class described having a back stop and arranged to permit unobstructed introduction of the shoe endwise against the back stop, combined with means for severing the inseam stitches and means for actuating said stitch severing means.

45. A machine of the class described having a back stop and arranged to permit unobstructed introduction of the shoe endwise against the back stop, combined with mechanically operated means constructed and arranged for severing the inseam stitches on the two sides of the shoe simultaneously and at the same distance from the end of the shoe.

46. A machine of the class described having means for cutting a welt and means constructed and arranged for cutting shoe stock of the inseam even with the lower face of the welt and actuating mechanism for said two means.

47. A machine of the class described having means for butting the two ends of a welt at the same time and additional means for detaching the two cut off end portions of the welt from the shoe at the same time.

48. A machine of the class described having means for butting a welt and a support for the welt butt arranged for movement transversely of the shoe from an inoperative position remote from the shoe into an operative position under the welt butt.

49. In a machine of the class described, means arranged for movement transversely of the shoe under the welt for planing the

stock of the inseam adjacent to the heel seat substantially level with the upper on the shoe bottom.

50. In a machine of the class described, the combination with two cutters arranged at an angle and having intersecting paths of movement, and means for actuating one of said cutters lengthwise of the cutting edge of the other cutter.

10 51. In a machine for removing surplus stock, the combination with two cutters, of means for actuating one cutter into position to support the surplus stock for the action of the other cutter.

15 52. In a machine of the class described, the combination with welt butting means, of stitch cutting means movable from an inoperative position into position to support the welt end for the action of the butting means.

20 53. In a machine of the class described, an operative tool having a portion formed to apply pressure through the inseam, and a portion formed to cut the stitches of the inseam.

25 54. A machine of the class described having means for butting the welt of a lasted and welted shoe and means for detaching the severed portion of the welt from the shoe.

30 55. A machine of the class described having a welt butting cutter combined with a stitch cutter and means for actuating the two cutters independently.

35 56. A machine of the class described having a stitch cutting blade comprising an acting edge with a sharpened portion to enter the stock through the inseam and a blunt portion to engage the stock at the inseam and limit the advance of the blade.

40 57. A machine of the class described having a blade comprising a blunt portion to engage the shoe stock in the welt crease to apply pressure and a sharpened portion to advance beyond the welt crease and cut the

stitches of the inseam, and means for actuating the blade.

58. A machine of the class described having devices arranged at either side of a welted shoe to overlie the shoe bottom and means for actuating said devices transversely of the shoe to remove surplus stock from the shoe bottom.

59. A welt butting apparatus, having in combination, a knife, a welt rest formed to support the welt end in angular relation to the path of the knife to determine the bevel at which the welt shall be butted, and means for securing the rest in different adjusted relations to the knife.

60 60. A machine for butting welts having, in combination, a cutter plate beneath and supporting the free end of the welt at an angle to the face of the insole, a welt cutter above the welt, means for relatively moving 65 said plate and cutter to position the cutter for the welt butting operation, and means for moving the cutter across the cutter plate to sever the welt end.

61. A machine for butting welts having, 70 in combination, a cutter plate beneath the welt, a welt cutter above the welt, said parts being relatively movable to permit a positioning of the cutter on the welt in advance of the cut, and means for operating the 75 cutter to sever the welt end.

62. A machine for butting welts having, in combination, a cutter plate beneath the welt, a welt cutter above the welt, and means for imparting to said cutter a positioning 80 movement toward the shoe bottom and thereafter a welt cutting movement in a direction at an angle to the positioning movement.

In testimony whereof I affix my signature, 85 in presence of two witnesses.

ERASTUS E. WINKLEY.
